UNITED STATES PATENT OFFICE.

MORRIS SCHIFF, OF BRONX, NEW YORK.

ADJUSTABLE-SIZE CAP.

Application filed February 9, 1924. Serial No. 691,570.

To all whom it may concern:

Be it known that I, MORRIS SCHIFF, a citizen of Russia, and residing at Bronx, in the county of Bronx and State of New York, have invented certain new and useful Improvements in Adjustable-Size Caps, of which the following is a specification, such as will enable those skilled in the art to which it appertains to make and use the same.

This invention relates to caps and particularly to caps provided with means for adjusting the size thereof to provide the proper fitting of the cap to the head of the wearer, and the object of the invention is to provide an improved cap of the class specified which is so constructed as to provide a finished and unobstructed lining for the cap when in its fully extended position, means being provided whereby in the reduction of the size of the cap the lining and body portion of the cap telescope or fold inwardly into the space between the lining and facing of the cap and provide a neat and finished appearance to the complete cap when in extended and contracted position, and with these and other objects in view the invention consists in a cap of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective side view of a cap made according to my invention and showing the same in a fully contracted position;

Fig. 2 is a sectional view on the line 2—2 of Fig. 1;

Fig. 3 is a partial section on the line 3—3 of Fig. 2; and,

Fig. 4 is a diagrammatic view of one side portion of the cap on an enlarged scale and with parts extended and broken away.

In the drawing I have shown for the purpose of illustrating one method of carrying my invention into effect, what is known as a pleated cap 10 having pleats 11 extending about the periphery thereof and merging into the crown portion 12, and at 13 is shown the band portion of the cap, and at 14 the peak thereof and, in the construction

of the cap, the facing 12 from which the crown is formed extends downwardly and is secured to the band portion 13 from substantially the point 16 at one side of the cap 60 around the back of the cap to substantially the point 17 at the opposite side thereof, and the band 13 extends freely at the front of the cap in the form of two strap members 18 and 19 adjustably secured together by a 65 buckle construction 20.

Mounted in the front band portion of the cap, or in the material of the crown 12 or in a fold therein which extends downwardly to the peak 14 in forming this band 70 portion of the cap, is a stiffening band or strip 21 of buckram or similar material which projects through the band beyond the points 16 and 17 as clearly shown in Fig. 2 of the drawing, and these projections form 75 tongues, which facilitates the contraction of the cap or band portion thereof as herein-after set out.

The lining 22 of the cap is continuous as is the custom in the construction of caps in 80 common use; in other words no pockets, slits or the like are formed therein as is the common practice in adjustable caps of the class under consideration that are now in use. The lining 22 is stitched to the front 85 band portion of the cap at the sides thereof as shown at 23 in Fig. 4 of the drawing by a vertical line of stitching, which also passes through the facing material 15 which is extended to form the band 13 at the front of 90 the cap but between the points 23 and extending backwardly around the cap the lining 22 is free from the band 13 and the material 15 of the crown 12 to form a space or chamber 24. It will be understood that the 95 lower edge of the lining 22 is secured to the band 13 and material 15 of the crown as shown at 25 in Fig. 3 of the drawing.

With the above described construction when the cap is fully extended as illustrated in Fig. 4 of the drawing, the lining 22 will be smooth and unobstructed, or will conform with the shape of the cap as extended, and this will also be true of the facing material 15 forming part of the band portion 100 13 of the cap at the front and front sides thereof as indicated at 26 in Fig. 4 of the drawing, and if it be desired to fully contract the band of the cap to the smallest size or to a smaller size than the fully expanded 105 or largest size, the strap members 18 and 19 are separated and the side portions of the

front part of the band 13 in juxtaposition to the peak 12 are forced inwardly, in which operation the projecting members of the reinforcing band 21 extend into the chamber 24 at the opposite sides of the cap, and the lining 22 and facing 15, at 26, telescope or fold into the chamber 24 as indicated at 27 in Fig. 2 of the drawing. When the desired adjustment has been made the strap members may be recoupled together and the cap is now ready for use.

The distinctive feature of my invention resides in the method of constructing the opposite side portions of the cap rearwardly of the peak 14 and in the band portion 13 thereof, and especially in the provision of a continuous unobstructed or otherwise fashioned lining forming a neat and finished inner appearance to the interior of the cap as well as the formation of a neat and finished appearance to the exterior of the cap at the points 16 and 17. It will be also noted that the inward telescoping or folding of the facing material 15 extends into one side of the pleats 11 which are purposely positioned at the opposite sides of the cap, see Figs. 1 and 4, thus making the fold at 27 invisible from the exterior of the cap. It will be understood that while I have shown certain details of construction for carrying my invention into effect that I am not necessarily limited to these details, and various changes therein and modifications thereof may be made, within the scope of the appended claims, without departing from the spirit of my invention or sacrificing its advantages.

Having fully described my invention, what I claim as new and desire to secure by Letters Patent, is:-

1. An adjustable size cap of the class described comprising a crown portion, a band portion and a peak, said crown portion being composed of facing material and a circumferentially continuous lining therefor, said lining extending onto the band portion of the cap and constructed to form a chamber in the band portion of the cap between said lining and the facing material of the cap, said lining and facing material being secured together at opposite front side portions of the cap and the band portion of the cap at a predetermined distance rearwardly of the coupling of the lining with the facing the facing being free from the body portion of the cap and extending to form strap members.

2. An adjustable size cap of the class described comprising a crown portion, a band portion and a peak, said crown portion being composed of facing material and a circumferentially continuous lining therefor, said lining extending onto the band portion of the cap and constructed to form a chamber in the band portion of the cap between said lining and the facing material of the cap,

said lining and facing material being secured together at opposite front side portions of the cap and the band portion of the cap at a predetermined distance rearwardly of the coupling of the lining with the facing being free from the body portion of the cap and extending to form strap members, and said lining and facing material being adapted to telescope into said chamber at the opposite sides of the cap where the strap members join said band.

3. An adjustable size cap of the class described comprising a crown portion, a band portion and a peak, said crown portion being composed of facing material and a circumferentially continuous lining therefor, said lining extending onto the band portion of the cap and constructed to form a chamber in the band portion of the cap between said lining and the facing material of the cap, said lining and facing material being secured together at opposite front side portions of the cap and the band portion of the cap at a predetermined distance rearwardly of the coupling of the lining with the facing being free from the body portion of the cap and extending to form strap members, said lining and facing material being adapted to telescope into said chamber at the opposite sides of the cap where the strap members join said band, and semi-rigid members forming extensions to the front band portion of the cap and adapted to extend into said chamber.

4. An adjustable size cap of the class described composed of a facing and lining, said facing and lining being continuous circumferentially at the head opening portion of the cap, the band portion of the cap being constructed on opposite sides thereof in such manner as to provide for the telescoping of the facing and lining material into a chamber formed between said lining and facing.

5. An adjustable size cap of the class described composed of a facing and lining, said facing and lining being continuous circumferentially at the head opening portion of the cap, the band portion of the cap being constructed on opposite sides thereof in such manner as to provide for the telescoping of the facing and lining material into a chamber formed between said lining and facing, and strap members for retaining the band of the cap in predetermined positions of adjustment.

6. An adjustable size cap of the class described composed of a facing and lining, said facing and lining being continuous circumferentially at the head opening portion of the cap, the band portion of the cap being constructed on opposite sides thereof in such manner as to provide for the telescoping of the facing and lining material into a chamber formed between said lining and facing, strap members for retaining the band of

the cap in predetermined positions of adjustment, and semi-rigid members at the opposite sides of the cap to facilitate the telescoping of the facing and lining.

- 5 7. In a cap of the class described having facing and lining materials, continuous circumferentially at the head opening portion of the cap, chambers formed between said lining and facing at the opposite sides of the cap, and tongue members at the opposite sides of the cap whereby said lining and facing materials are adapted to be telescoped into said chambers in the size adjustment of the cap.
- 10 8. In a cap of the class described having

facing and lining materials, continuous circumferentially at the head opening portion of the cap, chambers formed between said lining and facing at the opposite sides of the cap, tongue members at the opposite sides of the cap whereby said lining and facing materials are adapted to be telescoped into said chambers in the size adjustment of the cap, and means for retaining the cap in predetermined positions of adjustment. 25

In testimony that I claim the foregoing as my invention I have signed my name this 7th day of Feb. 1924.

MORRIS SCHIFF.
